UNITED STATES PATENT OFFICE.

NERSES HAROUTIN MAHTESIAN, OF WATERTOWN, NEW YORK.

RAILWAY GATE.

Application filed March 22, 1923. Serial No. 626,880.

To all whom it may concern:

Be it known that NERSES HAROUTIN MAHTESIAN, a citizen of the United States, residing at Watertown, in the county of Jefferson and State of New York, has invented certain new and useful Improvements in Railway Gates; and he does hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to railway gates and has for an object to provide a new and improved type of gate, automatically operated from the closing of electric circuits by the passing of trains.

A further object of the invention is to provide gates for roadways or the like adapted to swing or otherwise close over the passage of roadways across railway tracks, with improved mechanical means for actuating said gates and with train operated electrical means for actuating said mechanisms.

With these and other objects in view, the invention comprises certain novel elements, parts, units, combinations, mechanical movements, functions and interactions as disclosed in the drawings, together with mechanical equivalents thereof as will be hereinafter more fully described and claimed.

In the drawings:

Figure 1 is a top plan view of the device, certain parts being broken away for showing underlying parts;

Figure 2 is a view of the structure in side elevation;

Figure 3 is an enlarged detail view, partly in plan and partly in section, of the transmission mechanism;

Figure 4 is a view in side elevation of the momentum operated release mechanism.

Figures 5, 6 and 7 are diagrammatic representations of the several movements of the release.

Figure 8 is a perspective view of the lever part of the release mechanism.

Like characters of reference indicate corresponding parts throughout the several views.

The improved gate mechanism which

forms the subject-matter of this application is adapted to close passageways across railway tracks, whether such passageways are roadways or other railroad tracks, but having special reference to the closing of highway crossings. The device is intended to be mounted in a pit beneath the level of the railway track, such track being represented by the diagrammatic rails, 10.

In the necessary pit or other depression, a base, 11, is provided, supporting the structure, consisting in part of an electric motor, 12. At any convenient point along the rails, 10, train operated switches 13 and 14 are installed with a source of electrical energy, 15, in circuit therewith. As there are now known many types of train operated switches which will perform the function required in the present case, no attempt has been made to show any specific form of switch, but to represent the switch only diagrammatically.

The armature of the motor connects directly with stub shaft, 16, rigidly connected with a cross head, 17, rotating with said armature within a drum, 18.

Pivoted to the cross head, 17, are friction clutch members, 19, adapted under the centrifugal action of the rotation of the cross head to expand into frictional engagement with the interior of the drum, 18.

Mounted slidably and rotatively upon the shaft, 16, is also a sleeve, 20, to which sleeve the extremities of the friction clutch members, 19, are connected by flexible links, or the like, 21. It will be obvious, especially from an examination of Figure 2, that as the clutch members 19 expand under centrifugal action the flexible connections 21 will tend to rotate the sleeve, 20 in advance of its normal rotation with the shaft, 16.

The sleeve, 20, is provided with a cam notch, 22, and a pin, 23 is mounted upon the shaft 16, so that the augmented rotary action of the sleeve, 20, in the direction indicated by the arrow at Figure 3 will tend to move said sleeve with its cam notch, 22, upon said pin, and therefore to force this longitudinally along the shaft 16.

This sleeve, 20, is provided with a groove, 24, which is engaged by pins, 25, of the bifurcated end, 26, of the bell-crank lever shown in perspective at Figure 8. This bell-crank lever is fulcrumed at 27 to swing in normal horizontal planes and an arm, 28, preferably integral therewith, is connected

with a spring, 29, tending to hold said integral device with the arm, 28, at its limit of movement adjacent the plane of the drum, 18.

5 The drum, 18, is rigidly connected with a shaft, 30, which carries a worm, 31, intergeared with a worm-gear, 32, rigidly mounted upon the shaft, 33. The shaft, 33, is journaled in any approved part of the structure, as indicated at 34, and carries a worm, 35, intergeared with the worm gear, 36. This gear, 36, is loosely mounted to rotate upon the shaft 37, journaled in any approved manner, as at 38, and is provided 10 with a plurality of sockets, 39, in its face or, as shown more particularly at Figure 3, in a plate, 40, rigidly secured to the gear by means of screws, 41.

20 The shaft, 37, carries a crank arm, 42, with a hollow wrist pin, 43, the axis of which coincides with the circle upon which the sockets, 39, are formed.

25 Within the hollow wrist pin, 43, a plunger, 44, is mounted (see Figure 3) with a spring, 45, engaging a head, 46, an extremity, 47, being provided properly proportioned and positioned to enter one of the sockets, 39, under the action of the spring when released.

30 The plunger, 44, is provided with a head, 48, perforated and sliding upon a pin, 49, rigidly secured to the wrist pin, 43, which prevents rotation of said head.

35 Adjacent to the normal position of this head, 48, a rocker arm, 50, is mounted upon a shaft, 51, journaled in any approved manner, as at 52. The rocker arm, 50, is provided at opposite ends with cams, 53, positioned to engage the cam surface, 54, of the head, 48. As shown at Figure 5, the relation of the cam surfaces 53 and 54 is such that the plunger 44 has been withdrawn to the position shown at Figure 3, disengaging the plunger from engagement with sockets, 39.

40 When the extremity of the rocker arm, 50, is lifted to the position shown at Figure 6, it permits the spring, 45, to throw the plunger extremity, 47, into engagement with the gear, 36, or plate, 40, and to engage any one of the sockets, 39, presenting itself for such purpose. For rocking the rocker arm to produce this result, a finger, 55, is rigidly secured to the shaft, 51, with means, as the spring, 56, for holding the rocker arm in normal position, such normal position being limited by a pin, 57.

45 Preferably as an integral part of the bell-crank lever, 26, an arm, 58, is provided having a detent, 59, pivoted thereto at 60 and held yieldingly by a spring, 61. The detent, 59, is provided with a cam extremity, 62, so positioned and proportioned that when the bell-crank lever swings under the movement of the sleeve, 20, the cam extremity,

62, engages against the finger, 55, and rocks the rocker, 50, so that its cam extremity, 53, rides up from the position shown at Figure 5 to the position shown at Figure 6, permitting the plunger, 44, to pass under the extremity, as indicated at Figure 7.

50 For a return movement, the detent, 59, yields by reason of the spring 61 passing the finger 55 without acting.

55 Pivoted to the wrist pin, 43, is a connecting rod, 63, which in turn is pivotally connected with a rack, 64, mounted to reciprocate in any approved way, formed in the base, 11.

60 Journaled upon the base 11, are shafts, 65 and 66, intergeared with the rack, 64, by means of pinions, 67 and 68, respectively. The shafts 65 and 66 carry beveled gears, 69

and 70, intergeared with gears 71 and 72, rigidly connected respectively with vertical 85 shafts 73 and 74. To the shafts, 73 and 74, are respectively connected gate panels, 75

and 76, intended to span the interval between the shafts 73 and 74, which will be normally located upon opposite sides of the highway, if the device is operated in conjunction with a highway. It is the intent to provide these gates with signal or danger

lights, indicated at 77, but the manner of illumination is not shown here, as it is within the knowledge of any electrician to supply such lights in such a position as may be necessary or desirable.

90 It will be noted from Figures 1 and 2 and the position of the parts at Figure 3, that the gates are in closed position. This, of course, is assuming that a train has entered

95 the block and has actuated the parts by the operation of the mechanism to such closed position. When leaving the block, a train traveling in the direction indicated by the arrow at Figure 1 will close the switch 13.

100 The circuits connected with this switch and with the motor are so simple as to require no definite explanation. It will be obvious

105 that the closing of this switch will energize the motor, 12, rotating the shaft, 16, and therewith the cross head, 17. The rotation of this cross head, 17, will cause the clutch

110 member 19 to expand by centrifugal force into engaging position with the interior of the drum, 18, and to thereby rotate the shaft, 30, and, through the train of worms, the gear 36. The crank arm, 52, and wrist

115 pin, 43, will not, however, be rotated with the parts in this position, for the reason that the plunger, 44, is not in engagement.

120 The expansion of the clutch members, however, has rotated the sleeve, 20, in advance of the rotation of the shaft and has, therefore, moved the sleeve longitudinally by

125 reason of the cam action. This movement of the sleeve, acting upon the lever shown at Figure 8, will cause the cam extremity of the detent, 59, to engage against the finger,

55, to rack the rocker, 50, from the position shown at Figure 5 to the position shown at Figure 6 and the spring, 45, will throw the plunger, 44, from the position shown at 5 those figures to the position shown at Figure 7. This throws the extremity, 47, into position to engage any one of the sockets, 39, as the gear, 36, rotates. The engagement being effected, the crank arm, 42, and 10 wrist pin, 43, will rotate. This will cause the rack, 64, to be moved longitudinally from the position shown at Figures 1 and 2 towards the gear mechanism. When the 15 wrist pin has made one half a revolution to retract the rack to the limit of its movement, the head, 48, of the plunger, 44, will engage the cam, 53, upon the opposite end of the rocker, 50, and will be withdrawn from engagement with the sockets, 39, 20 whereby the rack will immediately come to rest and the gear mechanism may continue to operate so long as its momentum may impel, or the current continue to be supplied from any source.

25 With the gates thus opened by the reciprocation of the rack, 64, the wrist pin, 43, will assume a position opposite to that shown at Figures 1, 2 and 3, and this position may, perhaps, be considered the normal position, as the gates in open position no doubt would be considered normal. With a train entering the block, however, either one of the switches, 13 or 14, being closed, the motor is again energized and the 30 action of all the parts is repeated identically the same, with the exception of the movement of the rack in the opposite direction, closing the gates. It will be obvious, therefore, that the rotation of the motor and all 35 its intergeared and related parts is always in the same direction and that the reciprocating movement of the rack is interrupted at its limits by the interposition of the rocker arm, 50, retaining thereby the gates 40 in their open or closed position as they assume by such movement to remain in such position until the mechanism is again energized from closing either the switch 13 or 45 14 by the passing of the train over or in 50 contact with said switches.

The utility of the connection effected by the plunger, 44, will be apparent in that it permits the overcoming of the inertia of the parts from the motor before the resistance 55 of operating the gates is thrown onto said mechanism. It is also true in regard to the clutch members, 19, which are held normally out of clutching engagement with the drum, 20, until the motor has started and 60 attained sufficient speed to throw said clutch members by centrifugal action outwardly into engagement making such engagement gradually, as in the case of friction clutches, starting the mechanism and overcoming the 65 inertia of the gearing before the wrist

pin, 43, is connected with the gear, 36, or plate, 40, whereby the device may be operated with a smaller motor and a less consumption of current than where the initial torque of the motor is directly upon the 70 mechanism, actuating all of the structure, including the swinging of the gates.

While the gates have been shown as mounted upon the vertical shafts and swinging in horizontal planes, it is obvious that 75 the rack, 64, may be employed to operate other mechanical devices than the vertical shafts and horizontally swinging gates, and that in positions where gates otherwise operated are necessary, desirable or preferable, 80 the reciprocating motion of the rack, 64, may be translated into other mechanical movements than those specifically shown in the drawings.

What I claim to be new is:

1. The combination with movable gates of a reciprocating rack, a crank arm connected with the rack, a train of gearing, means to at times connect the crank arm with the train of gearing, a motor, a friction clutch 90 interposed between the motor and the gearing, means actuated by the mechanism of the motor for actuating the friction clutch, means actuated from the friction clutch to engage the crank arm with the train of 95 gearing.

2. The combination with movable gates of a reciprocating rack positioned to actuate said gates, a crank arm, means connecting the crank arm with the rack, a gear rotating concentrically with the crank arm, means to at times connect the crank arm with the gear, a train of gears intergeared with said arm, actuating gear and motor, a centrifugal clutch operated by the motor 100 and adapted to operate the train of gears, and means operated by the centrifugal clutch for initiating connection between the crank arm and its gear.

3. The combination with movable gates 110 of a reciprocating rack connected therewith, a crank arm, a connecting rod extending from the crank arm to the rack, a spring pressed plunger carried by the crank arm, a gear rotating concentrically with the crank 115 arm and provided with sockets for receiving the plunger, a train of gears operating said crank arm gear, a motor, a clutch interposed between the motor and the train of gears, a trigger positioned to withdraw the plunger from connecting the crank arm with its gear, and means operated by the clutch for throwing the trigger to releasing position.

4. The combination with movable gates of 125 a reciprocating rack adapted to actuate said gates, a crank arm, a hollow wrist pin carried by the crank arm, a connecting rod connecting the wrist pin with the rack, a plunger mounted to reciprocate within the hollow 130

wrist pin, a spring positioned to yieldingly actuate said plunger, a gear journaled concentrically with the crank arm and provided with a plurality of sockets concentric with the plunger, a trigger positioned to withdraw the plunger from the sockets against the tension of the spring at diametrically opposite points in the movement of the crank arm defining the limits of movement of the rack, a motor, a clutch connected with the motor, means intergearing the clutch with the crank arm operating gear, and means actuated by the clutch to release the trigger at a properly timed interval following the starting of the motor.

5. The combination with movable gates

of mechanism for actuating the gates, a trigger positioned to interrupt the gate actuating mechanism at its limits of movement, a motor, a clutch connected with the motor and adapted to actuate the gate operating mechanism, a sleeve mounted to slide upon the motor shaft, means actuated by the clutch to rotate the sleeve relative to the motor shaft, a cam tending to move the sleeve longitudinally upon the shaft when rotated relative thereto and means actuated by the sliding of the sleeve for releasing the trigger.

In testimony whereof he hereunto affixes his signature.

NERSES HAROUTIN MAHTESIAN.
